United States Patent Office

Des. 184,110
Patented Dec. 16, 1958

184,110

AUTOMOBILE GRILLE UNIT OR THE LIKE

Edward G. Mueller, Omaha, Nebr., assignor to General
Motors Corporation, Detroit, Mich., a corporation of Delaware

Application May 26, 1958, Serial No. 51,078

Term of patent 7 years

(Cl. D54—2)

The figure is a perspective view of an automobile grille unit or the like embodying my new design.

I claim:

The ornamental design for an automobile grille unit or the like, substantially as shown.
